EXPANSIBLE LINK CHAIN FOR A BRACELET OR THE LIKE

Emil E. Fachon, Edgewood, R. I., assignor to
Bulova Watch Company, New York, N. Y., a
corporation of New York

Application May 8, 1951, Serial No. 15,103

Term of patent 3½ years

(Cl. D45—4)

To all whom it may concern:

Be it known that I, Emil E. Fachon, a citizen of the United States, residing at Edgewood, county of Providence and State of Rhode Island, have invented a new, original, and ornamental Design for an Expansible Link Chain for a Bracelet or the like, of which the following is a specification, reference being had to the accompanying drawing, forming part thereof.

Fig. 1 is a top plan view of the expansible link chain in contracted condition, showing my new design;

Fig. 2 is an end view of the expansible link chain shown in Fig. 1;

Fig. 3 is an edge elevational view of Fig. 1;
Fig. 4 is a bottom view of Fig. 1;

Fig. 5 is a top plan view of the expansible link chain shown in Fig. 1 with the links in an expanded position; and

Fig. 6 is an enlarged plan view of one of the top links.

I claim:

The ornamental design for an expansible link chain for a bracelet or the like, as shown and described.

EMIL E. FACHON.
